UNITED STATES PATENT OFFICE.

CHARLES HAMMER, OF QUEENS, NEW YORK, ASSIGNOR, BY DIRECT AND MESNE ASSIGNMENTS, TO AMERICAN METAL CAP CO., OF BROOKLYN, NEW YORK.

SCALLOP CAP.

1,308,746.

Specification of Letters Patent.

Patented July 1, 1919.

Continuation of application Serial No. 841,308, filed May 27, 1914. This application filed April 27, 1917. Serial No. 164,832.

To all whom it may concern:

Be it known that I, CHARLES HAMMER, a citizen of the United States, residing at Queens, in the county of Queens and State 5 of New York, have invented certain new and useful Improvements in Scallop Caps, of which the following is a specification.

This invention is a continuation of my previous application now forfeited, Serial 10 No. 841,308, filed May 27, 1914, and relates to closures for storage vessels that are secured on bottles and jars having screw-threads or lugs on the neck, and which closures are provided with projections extending 15 inward and arranged in the form of partial screw-threads, to engage the lugs and cause the closure to be screwed securely down on the top of the bottle.

One object of the present invention is to 20 provide a kind of lug that is formed by bending upwardly projections on the cap flange, in such a manner that each lug will present a raw edge in position to directly engage the lug or thread on the bottle neck, 25 and each lug will also present a bent portion of the projection to engage the thread on the bottle.

A further object of the invention is to 30 provide a form of the thread engaging projection that is so disposed relative to the screw-thread on the bottle neck that the pitch of the threads in the two coöperating members are slightly different, whereby the 35 projection will first engage with the thread on the bottle at the portion provided with the raw edge, and upon further application of the closure by screwing it down, the projection will slightly yield at the engaging portion to cause engagement throughout the 40 extent of the projection with the bottle thread.

A further object is to provide in connection with the described form of cap, strengthening means extending around the 45 flange adjacent the said projections, in the nature of a rib or corrugation.

In the accompanying drawings showing 50 embodiments of my invention, Figure 1 is a vertical central section through the closure before the flanges are bent up to their final form. Fig. 2 is a similar view of the finished closure, with the jar threads indicated. Fig. 3 is a fragmentary bottom plan view of the closure. Fig. 4 is a fragmentary section 55 enlarged on the line 4—4 of Fig. 3. Fig. 5

is a fragmentary section enlarged on the line 5—5 of Fig. 3. Fig. 6 is a fragmentary section enlarged on the line 6—6 of Fig. 3. Fig. 7 shows a section of a modification, with the projections before bending, and Fig. 8 shows the same in the bent form. Fig. 9 is a fragmentary bottom plan of the closure shown in Fig. 8. Fig. 10 is an enlarged section on the line 10—10 of Fig. 8. Fig. 11 is an enlarged section on the line 11—11 60 of Fig. 8. Fig. 12 is an enlarged section on the line 12—12 of Fig. 8.

In the arrangement shown in Figs. 1—6, I provide a cap comprising a top 18 and a flange 19 of cylindrical form, on the bottom of which are series of projections 20, four being shown. Each of these projections is so formed that when it is bent over inwardly at an angle to the top plane of the cap it will be inclined thereto, and will also 70 be curved corresponding to the cylindrical curve of the flange; and further the edge of the margin is given a kind of roll or bend whereby one portion, as at 21, will present a raw edge of the projection to the thread 75 22 of the jar, as indicated in Figs. 2 and 3. In this form of cap I provide the projections with a comparatively steep or abrupt edge 23 at one side, while the other side portion 24 is given a very gradual incline or slope. It will be seen that when 80 this projection is rolled or bent inwardly, the portion at 21 will be bent over about the amount of one-half circle, as shown by the section of Fig. 4, taken at this end of the projection. Fig. 5 is a section at the middle 85 portion of the projection and shows the bend extending farther toward the flange portion 19. At the other end of the projection the bend extends still farther in the form of a 90 roll or bead, as indicated in Fig. 6. It will be further observed from these three sectional views, that as the bend approaches the projection, it is located a greater distance 95 from the top. By reason of this construction 100 of the projection or lug, the portion 21 will present a raw edge to engage the thread on the jar, while the other two portions will present practically a bent edge or portion.

It will be further seen from Fig. 2 that the 105 angle which the portion of the lug that engages with the thread 22, makes with the thread, is of a slightly different pitch or inclination, whereby the portion 21 of the projection which has the raw edge forma- 110

tion, will first engage the thread 22. Upon further application of the cap this part of the projection will yield slightly sufficient to cause engagement with the bottle thread 5 throughout the length of the projection.

In Figs. 7-12 is shown a modification in which a cap having the flange 26 is provided with projections 27 that have one side edge abruptly inclined at 28, and the opposite side at 29 having a very gradual incline or slope, and the projection is further provided with an abrupt shoulder at 30, whereby one portion of the projection extends for a greater depth from the top of the cap than 10 the other portion, when the projections are first formed, as indicated in Fig. 7. When these projections are rolled inwardly at an incline to the top of the closure, a raw edge will be provided at 31 adjacent the inclined 15 side edge 29 of the projection, as indicated in Figs. 9 and 10. The portion beyond the shoulder 30 will be bent inwardly as indicated at 32 in Figs. 9 and 12. The intermediate portion 33 is indicated in Fig. 11. 20 This projection in its final form may also be given a pitch slightly different from the pitch of the thread 34 on the bottle neck, as indicated in Fig. 8.

When either of these forms of closures 30 are applied to a threaded bottle neck, the raw edge will cause the projection or lug to engage with a very strong friction that will assist in securely retaining the closure on the jar. The projections will also yield 35 and cause engagement throughout the extent of the projections, with the threads or lugs on the bottle neck.

Having thus described my invention, what I claim is:—

40 1. A closure for a storage vessel comprising a flanged cap having a plurality of projections each bent over inwardly to form lugs on the inside of the flange adapted to engage the screw thread on a jar, each lug presenting to the jar thread an initially engaged raw edge of the projection and also a bent portion of the projection adapted to be pulled inwardly toward the jar by said raw edge.

45 2. A closure for a storage vessel comprising a flanged cap having a plurality of projections each bent over inwardly to form lugs on the inside of the flange adapted to engage the screw thread on a jar and having a greater inclination than the jar thread, each projection having a steep edge on one side with the other side edge of the projection gradually inclined, each lug presenting to the jar thread a raw edge of the projection and also a bent portion of the projection.

50 3. A closure for a storage vessel comprising a flanged cap having a plurality of projections each bent over inwardly to form lugs on the inside of the flange adapted to

engage the screw thread on a jar, each lug presenting to the jar thread a raw edge of the projection and also a bent portion of the projection, the said lugs being so inclined and the said engaging raw edge of the lug and the bent edge of the lug being so arranged relative to the engaging portion of the jar thread, whereby to cause the raw edge to engage the thread previous to engagement of the bent edge therewith. 70

4. A closure for a storage vessel, comprising a flanged cap having a plurality of projections each of which has one side of greater depth from the top of the cap than the other portion with an abrupt shoulder between such portions, said projections being bent over inwardly to form lugs on the inside of the flange adapted to engage screw threads on a jar, each lug having one of its said portions presenting a raw edge to the jar thread and the other said portion presenting a bent edge to the jar thread. 80

5. A closure for a storage vessel, comprising a flanged cap having a plurality of projections each of which has one side of greater depth from the top of the cap than the other portion with an abrupt shoulder between such portions, said projections being bent over inwardly to form lugs on the inside of the flange adapted to engage screw threads on a jar, each lug having one of its said portions presenting a raw edge to the jar thread and the other said portion presenting a bent edge to the jar thread, the longer of said projection portions having a steep side edge and the other said portion having the side gradually inclined. 90

6. A closure for a storage vessel, comprising a flanged cap having a plurality of projections each of which has one side of greater depth from the top of the cap than the other portion with an abrupt shoulder between such portions, said projections being bent over inwardly to form lugs on the inside of the flange adapted to engage screw threads on a jar, each lug having one of its said portions presenting a raw edge to the jar thread and the other said portion presenting a bent edge to the jar thread, said engaging raw edge of the lug and the bent edge of the lug, being arranged relative to the engaging portion of the jar thread whereby to cause the raw edge to engage previous to the engagement of the bent edge. 100

7. A closure for a storage vessel, comprising a flanged cap having a plurality of projections each of which has one side of greater depth from the top of the cap than the other portion with an abrupt shoulder between such portions, said projections being bent over inwardly to form lugs on the inside of the flange adapted to engage screw threads on a jar, each lug having one of its said portions presenting a raw edge to the jar thread and the other said portion pre- 120

- senting a bent edge to the jar thread, the longer of said projection portions having a steep side edge and the other said portion having the side gradually inclined, said engaging raw edge of the lug and the bent edge of the lug, being arranged relative to the engaging portion of the jar thread whereby to cause the raw edge to engage previous to the engagement of the bent edge.
10. 8. A closure for a storage vessel, comprising a flanged cap having a plurality of projections each of which has one side of greater depth from the top of the cap than the other portion with an abrupt shoulder between such portions, said projections being bent over inwardly to form lugs on the inside of the flange adapted to engage screw threads on a jar.
9. A closure for a storage vessel comprising a top and a flange, said flange having a plurality of extensions curled over inwardly to form bead like lugs of substantially uniform thickness on the inside of said flange, each lug being shaped to present an edge and a curved surface to the top of the closure, both said edge and the curved surface being designed to engage the vessel and enable the closure to seal the same.
10. A closure for a storage vessel comprising a top and a flange, said flange having an extension provided with a steep edge and a sloping edge, said extension being curled over and inwardly to form a lug on the inside of the flange, said lug being shaped so as to present an edge and a curved surface to the top of the closure, both said edge and said curved surface being designed to engage the vessel and enable the closure to seal the same.
11. A closure for a storage vessel comprising a top and a flange, said flange having a plurality of extensions each provided with a steep edge and a sloping edge, each extension being curled over and projecting inwardly to form a lug on the inside of the flange, each lug being shaped to present an edge and a curved surface to the top of the closure, both said edge and said curved surface being designed to engage the vessel and enable the closure to seal the same. 40
12. A closure for a storage vessel comprising a top and a flange, said flange being provided with extensions having a steep edge at one end and a sloping edge at the other and having an edge between the terminal edges 50 to enable the extensions to be curled over and project inwardly in order to form a lug on the inside of the flange, said lug being shaped to present an edge and a curved surface to the top of the closure, both said edge and said curved surface being designed to engage the vessel and enable the closure to seal the same. 45
13. A closure for a storage vessel comprising a top and a flange, said flange being provided with a plurality of extensions, each having a sloping edge at one end and an abrupt edge between said edges to enable the extensions to be curled over inwardly of the flange to 55 provide lugs, each of said lugs being shaped to present an edge and a curved surface to the top of the closure, both said edge and said curved surface being designed to engage the vessel and enable the closure to seal the same. 60
